(57) **CLAIM**

The ornamental design for a heat gun body, as shown and described.

DESCRIPTION

FIG. 1 is a front, left and top perspective view of a heat gun body showing our new design;

FIG. 2 is a rear, right and top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is a front, left and top perspective view of the heat gun body in accordance with our new design illustrating a state in which environmental structures (a battery and a nozzle) are attached to the heat gun body.

The broken lines in the drawings illustrate the environmental structures or portions of the heat gun body which form no part of the claimed design.
